UNITED STATES PATENT OFFICE.

NATHANIEL L. RIPLEY, OF BOSTON, MASSACHUSETTS.

DESIGN FOR A FINGER-RING.

SPECIFICATION forming part of Design No. 12,868, dated April 11, 1882.

Application filed March 2, 1882. Term of patent 3½ years.

To all whom it may concern:

Be it known that I, NATHANIEL L. RIPLEY, a citizen of the United States, residing at Boston, Suffolk county, State of Massachusetts, 5 have invented and produced a new and original Design for Finger-Rings, of which the following is a specification, reference being had to the accompanying drawing, forming part thereof.

10 The drawing shows in perspective a ring containing my design.

The ring herein shown as containing my design has its outer surface cut to form facets *a b*, thus leaving between the facets a zigzag band, 15 *c*, of uniform width. This zigzag band is ornamented or milled along its side edges, as at *d*, to form a border for the band *c*. The band is divided transversely by a row of dots or stipple-work, as at *e*, thus causing the band to resemble a series of parallelograms with their ends joined together. These parallelograms are further ornamented by scroll-work, as at *f*. The facets are ornamented near their centers by a figure, *g*.

20 25 I claim—

1. The design for finger-ring herein shown

and described, the same consisting of the facets *a b* at each side of a zigzag band of uniform width between the facets.

2. The design for finger-ring herein shown 30 and described, the same consisting of the facets *a b* at each side a zigzag band of uniform width, divided into parallelograms ornamented along their side edges.

3. The design for finger-ring herein shown 35 and described, the same consisting of the facets *a b* and the zigzag band of uniform width, ornamented along its central portion, as at *f*.

4. The design for finger-ring herein shown 40 and described, the same consisting of the facets *a b* and the zigzag central band of uniform width, ornamented along its edges and transversely, as at *e*, to form a series of parallelograms with their ends placed together.

In testimony whereof I have signed my name 45 to this specification in the presence of two subscribing witnesses.

NATHL. L. RIPLEY.

Witnesses:
